CLAIM

The ornamental design for an amusement car ride race track, as shown and described.

DESCRIPTION

FIG. 1 is a perspective view of an amusement car ride race track showing my new design; FIG. 2 is a front view of the amusement car ride race track; FIG. 3 is a left side view of the amusement car ride race track, the right side view being a mirror image thereof; and, FIG. 4 is a top plan view of the amusement car ride race track.

The undisclosed portions of the rear and bottom of the amusement car ride race track forms no part of the claimed design.
